(57) **CLAIM**

The ornamental design for a scissors grips, as shown and described.

DESCRIPTION

FIG. 1 is a perspective view of a scissors grips showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken line showing of the scissors blades in the figures illustrates the environment of the claimed design and forms no part thereof. The remaining broken lines illustrate portions of the scissors grips that form no part of the claimed design.
